UNITED STATES PATENT OFFICE

2,033,086

BUS OR CAR WINDOW CONSTRUCTION

Joseph Schunk, Newark, N. J., assignor to The National Lock Washer Company, Newark, N. J., a corporation of New Jersey

Original application January 12, 1934, Serial No. 706,367. Divided and this application November 23, 1934, Serial No. 754,438

4 Claims. (Cl. 189—76)

The present invention relates to a bus or car window construction, and the present application is a division of my application for Sash lock for bus or car window construction, Serial No. 5 706,367, filed January 12, 1934. It has for its object a window structure in which a sash lock may be conveniently incorporated in the bottom rail of a window sash, and whereby the sash lock will be inconspicuous, easy to operate, efficient 10 in operation, and in which the operating parts will at all times be held against rattling and vibration. It is proposed to provide a sash lock adapted to be incorporated as an inherent part of a bottom rail of known design, and particularly of the type as disclosed in the Letters Patent 15 for Bus or car window construction in the name of T. G. Conway, S. E. Blessin and J. Schunk, No. 1,976,773, dated October 16, 1934, without the necessity for materially altering such 20 bottom rail construction.

It is further proposed to provide a window construction in which the latch casing is provided as a part of the structure of the side strap of the sash, and which will constitute means for connecting the side strap to the bottom rail. Another object is to provide a window construction in which the sash lock parts may be readily assembled as a unit within the bottom rail, and also may be readily removed as a unit. A further 25 object is to provide a window construction in which the sash lock plunger is disposed and movable substantially in the vertical plane of the sash, and which is adapted to cooperate with a rack disposed in the side channel in which the sash slides, and which is also substantially in the central vertical plane of the sash, to the end that the sash lock is disposed within a minimum thickness, and a window construction is provided which is compact, neat in appearance, and of 30 maximum clear vision, all features highly desirable in bus or car window construction.

With the above and other objects in view embodiments of the invention are shown in the accompanying drawings, and these embodiments will be hereinafter more fully described with reference thereto, and the invention will be finally pointed out in the claims.

In the drawings:

Fig. 1 is a fragmentary front elevation showing the lower corner of a window construction in which is incorporated a sash lock, according to the exemplary illustrated embodiment of my invention.

Fig. 2 is a horizontal sectional view, taken 55 along the line 2—2 of Fig. 1.

Fig. 3 is a vertical sectional view, taken along the line 3—3 of Fig. 2, the lock plunger and its connected parts and also the sash glass, being shown in elevation.

Fig. 4 is a horizontal sectional plan view, taken 5 along the line 2—2 of Fig. 1; but with the sash glass removed.

Fig. 5 is a vertical sectional view, enlarged, taken along the line 5—5 of Fig. 1.

Fig. 6 is a vertical sectional view, enlarged, 10 taken along the line 6—6 of Fig. 1.

Fig. 7 is a perspective view of the lower end of the side strap having the sash lock casing member secured thereto.

Fig. 8 is a perspective view of the lock plunger 15 and connected parts.

Fig. 9 is a perspective view of the stop post employed.

Fig. 10 is a perspective view of the end portion 20 of the bottom rail.

Fig. 11 is an end elevation of the lower end of the side strap shown in Fig. 7.

Fig. 12 is a fragmentary stop plan view of a modified form of plunger and connected parts.

Fig. 13 is a top plan view of a modified front 25 of stop post.

Similar reference characters indicate corresponding parts throughout the several figures of the drawings.

Referring to the drawings, the window sash 30 according to my invention, and with which a sash lock is adapted to be incorporated, comprises a sash glass 1 having a top rail (not shown), a bottom rail 2, and a pair of vertical side straps 3 connecting the top and bottom rails, only one 35 of these straps being shown. The side straps are adapted to have vertical sliding movement in the channels mounted on the side posts, hereinafter more fully referred to.

The bottom rail 2 is of channel shape to receive 40 the lower edge of the sash glass. Upon the inner surface of each side of the channel longitudinally extending reinforcing ribs 4—4 are provided intermediate the top and bottom of the channel, and in the base of the channel there is provided a 45 longitudinal groove 5 of corresponding width to the spacing of the ribs 4—4, there being longitudinally extending grooves or recesses 6—6 in the respective sides of the channel between the ribs 4—4 and the longitudinal groove 5. The edge of 50 the glass 1 is bound with glazing tape 7, and when inserted in the channel of the rail the ribs 4—4 act as stops to limit the depth to which the glass may be engaged. According to my invention the sash lock is adapted to be inserted and housed 55

within the channel beneath the sash glass, and in mounting and connecting the same the sides of the channel are drawn into tight engaging relation with the glass, as will presently more 5 fully appear. Within a T-groove 8 in the lower end of the rail there is interlockingly engaged the T-rib 9 of a sealing strip 10, of rubber, felt or other suitable sealing material, for engaging upon the sill 11, a slot 12 being formed in the 10 under surface of said strip for rendering the strip more flexible.

The side strap 3 is in the form of a U-shape channel, and is adapted to receive the vertical edge of the glass, its vertical edges being bent 15 outwardly and rearwardly, as at 14—14, to engage the edge of the U-shape piece of facing material 15, which is cemented, riveted or otherwise suitably secured about the side strap, this material being of a suitable composition similar to 20 felt or leather as regards its wearing and sealing qualities and adapted to have easy sliding engagement in the side post channel.

The lower end of the side strap has secured 25 to it a tubular casing member 16 of rectangular cross section. For this purpose a pair of angle brackets 17—17 are secured to the sides of the casing by spot-welding or other suitable means, these brackets being engaged through slots 18—18 in the forward edges of the side strap having their 30 vertical portions engaged with the outer side surfaces of the side strap and secured thereto by spot-welding or other suitable means. The lower portion of the side strap has its sides slightly contracted, as indicated by the offset bends 19—19 35 in Figs. 7 and 8, so that the inner surfaces of the side strap are substantially flush with the vertical inner surfaces of the casing 16, while the outer surfaces above the offset bends 19—19 are substantially flush with the outer surfaces of the 40 brackets 17. A slot 20 is provided in the rear surface of the side strap in registering alignment with the passage through the casing 16 and a similar slot 21 is also provided in the facing material 15 for permitting the end of the lock 45 plunger to pass through, as will presently more fully appear. Holes 22 extend through the side straps 17 and the casing 16 for receiving the bolts employed in assembling the parts, as hereinabove more fully referred to.

50 The sash lock plunger 23 is in the form of an elongated rectangular cross-section bar having a beveled rack engaging nose 24 at its outer end and having a pair of guide slots 25 and 26 between its ends. A notch 27 is provided near its inner 55 end and is adapted to be engaged by the lug 28 of the operating lever 29, hereinafter more fully referred to. An extension rod 30 is provided upon the inner end of the plunger and has engaged thereon a U-shaped straddler or pressure member 60 31, an aperture 32 being provided in the intermediate portion of said member for sliding engagement upon the rod, and the sides of the member embracing the end of the plunger. The straddler member is normally pressed forwardly 65 toward the end of the plunger by means of the plunger spring 33 disposed about the rod 30 between the straddler member and a washer 34 slidably mounted upon the end of the rod and retained thereon by means of an enlargement 35 70 formed upon the end of the rod. It should be noted that the enlargement 35 serves to retain the washer spring and straddler member in place upon the plunger when these parts are in disassembled relation as a unit. In the assembled 75 relation in the sash rail the rod 30 is engaged

through the passage 36 of a stop post 37 secured in the groove 5 of the rail by means of a screw 38, this part being secured before attachment of the rubber sealing strip 10. The passage 36 is of larger diameter than the enlargement 35 so that the latter can be readily passed through it when assembling and disassembling the plunger and connected parts. In the assembled relation of the parts the washer 34 abuts the stop post compressing the spring 33, the stop post acting 10 as a fixed part against which the spring reacts.

The straddler member 31 is pressed back in the assembled relation, as shown in Figs. 3 and 4, so that its forward edges are substantially in line with or slightly forward of the edge of the recess 27, and normally presses against the lever lug 28, which in turn is pressed against the opposed side of the recess 27. In this way the lock parts and the operating lever are at all times held against looseness and rattling under pressure of 20 the spring 33, the straddler member being so arranged that it takes up all lost motion and compensates for wear and variations in the parts. This condition obtains even after considerable wear upon the parts and also under the continuous vibration to which the parts are subjected in the usual bus and car installations.

The plunger and its connected parts are assembled as a unit in the sash rail 2 with the side strap removed. Thereupon the side strap is 30 connected by first engaging the casing member 16 over the plunger and then forcing the casing member into the channel of the bottom rail 2, the longitudinal ribs 4—4 engaging the sides of the casing at its upper portion and the lower portion of the casing being engaged in the groove 5, while the portions of the brackets 17 at the sides of the casing engage in the grooves 6—6, as clearly shown in Fig. 5. As the side rail is forced to its limit position against the end of the bottom 40 rail the nose end 24 of the plunger projects through the slots 20 and 21 of the side strap. The parts are then secured in place by means of transversely disposed binding screws 39 and 40, each comprising an interiorly threaded socket 45 screw part and an exteriorly threaded screw part to engage the socket part, suitable countersunk holes 60 being provided in the bottom rail to receive these parts.

The binding screw 39 extends through the holes 50 22 in the casing 16 and brackets 17 and also extends through the slot 26 of the plunger, this screw serving to secure the side strap against displacement and also providing a movement limiting guide for the plunger. The binding screw 55 40 extends through the slot 26 of the plunger, and this binding screw is also utilized for securing one end of the operating lever casing, as will presently more fully appear. The engagement of the binding screws not only secures the 60 parts of the sash lock in place but draws the sides of the bottom rail tightly against the sides of the glass and also against the sides of the casing 16 and bracket 17 so that a rigidly assembled structure results.

The operating lever casing 41 is of substantially U-shape having an attaching ear portion 42 at one end which is secured to the side of the bottom rail by the binding screw 40 and a relatively elongated base portion at its other end which is 70 secured to the bottom rail by a binding screw 44. A window lift flange 45 is formed at the upper edge of the base 43 and is disposed beneath the finger engaging extension portion 46 of the operating lever 29, so that the latter may be con- 75

veniently operated by engaging the thumb with its upper side and the fingers with the lower side of the lift flange 45. The fulcrum lug 47 of the operating lever 29 is formed upon its face near its lower end and is pivotally seated in a recess 48 formed in the casing. The lug 28 of the operating lever extends to the interior of the bottom rail into engagement with the recess 27 of the plunger through an arcuate slot 49 formed in the side of the rail, and between the inner surface of the lever and the side surface of the rail there is provided a wear plate 50, also having an arcuate slot 51 registering with the slot 49, and provided with right angularly bent ends 52-52 which engage the ends of the casing. This wear plate protects the rail surface from the rubbing action of the lower part of the operating lever when the same is moved to operate the lock plunger.

20 The channel within which the side strap of the sash is slidably mounted comprises an outside stop 53 secured to the side post and an inside stop 54 removably connected to the outside stop constituting therewith a channel. Within this channel there is provided a rack 55 with which the lock plunger engages. It will be understood that the particular form of the side post channel and the means by which the rack is mounted therein forms no part of the present invention, 30 and that these parts may be of any desirable construction. As illustrated, the rack is mounted within a channel strip 56, being secured to the base of this strip by any suitable means as spot-welding or rivets. The edges of the strip are bent inwardly, as at 57-57, and bear upon the facing material 15, and a spring 58 is disposed between the base of the outside stop 53 and the base of the channel strip and presses the latter into snug engagement with the facing strip 15. 40 This construction provides a relatively narrow channel in which the rack is in alignment with the central vertical plane of the sash and is also effectually concealed.

In Figs. 12 and 13 I have shown a modified form of plunger and stop post adapted to be assembled in or removed from the sash rail without removal of the side strap. The plunger 23^b is swaged or otherwise reduced in thickness, as at 61, at its inner end adjacent the notch 27^b, the straddler or pressure member 31^b which engages over this portion being of a thickness no greater than the thickness of the plunger. The spring 33^b disposed about the extension rod 30^b is of a diameter no greater than the thickness of 55 the plunger, as is also the washer 34^b retained upon the rod by the enlargement 35^b. These parts may thus be inserted in and removed from the rail through the slot 20 in the side strap and through the tubular casing 16 without removing 60 these parts. The stop post 37^b having a passage 36^b, through which the rod 30^b engages, in the assembled relation, is also of such reduced thickness that it may be assembled or removed through the slot 20.

65 I have illustrated and described preferred and satisfactory embodiments of the invention, but it will be obvious that changes may be made therein, within the spirit and scope thereof, as defined in the appended claims.

70 Having thus described my invention what I claim and desire to secure by Letters Patent is:—

1. In a sash lock window construction, a horizontal rail having a longitudinally extending opening therein, a vertical side strap, a right angularly projecting tubular member of rectangular

cross-section having side walls and top and bottom walls secured to said side strap and engaged in the opening of said rail at one end and constituting a lock casing for receiving a longitudinally movable lock plunger of rectangular cross-section disposed in said opening and slidably engaged in said tubular member in sliding engagement at its four surfaces with the side and bottom and top walls thereof and projected from one end. 5

2. In a sash lock window construction, a horizontal rail having a longitudinally extending opening therein, a vertical side strap, a right angularly projecting tubular member of rectangular cross section having side walls and top and bottom walls secured to said side strap and engaged in the opening of said rail at one end and constituting a lock casing for receiving a longitudinally movable lock plunger of rectangular cross section disposed in said opening and slidably engaged in said tubular member in sliding 10 engagement at its four surfaces with the side and top and bottom walls thereof and projected from one end, and removable means secured to said rail extending transversely through said tubular member intermediate its top and bottom 15 walls to secure it in said opening and disposed in the path of said plunger and adapted to limit its projecting movement. 20

3. In a sash lock for window construction, a horizontal glass receiving rail having a longitudinally extending channel therein, said glass being disposed in the upper portion of said channel and the lower portion constituting a longitudinal opening, there being longitudinally extending grooves in the side walls of said lower 30 portion, a vertical channel side strap for receiving the vertical edge of the glass, a right angularly projecting tubular member of rectangular cross section having side walls and top and bottom walls, right angular brace members secured 35 at their horizontal legs at each side of said tubular member and secured at the vertical legs to said side strap, said tubular member being engaged in said longitudinal opening of said rail at one end with said horizontal legs of said brace 40 members engaged in said grooves, said tubular member constituting a lock casing for receiving a longitudinally movable lock plunger of rectangular cross section disposed in said opening and slidably engaged in said tubular member in sliding 45 engagement at its four surfaces with the side and top and bottom walls thereof and projected from one end, and removable means secured between the sides of said rail extending through the tubular member to secure it in said opening and to bind the sides of said rail against 50 said glass, the engagement of said horizontal legs of said brace members with said grooves adapted to prevent vertical displacement of said tubular member. 55

60 4. In a sash lock window construction, a horizontal rail having a longitudinally extending opening therein, there being longitudinally extending grooves in the side walls of said opening, a vertical side strap, a right angularly projecting tubular member of rectangular cross section having side walls and top and bottom walls, right angular brace members secured at their horizontal legs at each side of said tubular member and secured at their vertical legs to said side strap, said tubular member being engaged in the opening of said rail at one end and constituting a lock casing for receiving a longitudinally movable lock plunger of rectangular cross section 70 75

disposed in said opening and slidably engaged in said tubular member in sliding engagement at its four surfaces with the side and top and bottom walls thereof and projected from one end, means
5 secured to said rail adapted to secure said tubular member in said opening against longitudinal dis-

placement, the engagement of said horizontal legs of said brace members with said grooves adapted to prevent vertical displacement of said tubular member.

JOSEPH SCHUNK. 5
